(57) **CLAIM**
The ornamental design for a fin-plate for heat exchanger, as shown and described.

DESCRIPTION

FIG. 1 is a front elevational view of a fin-plate for heat exchanger, showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is an enlarged left side elevational view thereof;

FIG. 8 is an enlarged partial front elevational view thereof; taken along lines 8-8 of FIG. 1;

FIG. 9 is an enlarged partial front elevational view thereof; taken along lines 9-9 of FIG. 1;

FIG. 10 is an enlarged partial top plan view thereof; taken along lines 10-10 of FIG. 5;

FIG. 11 is an enlarged partial bottom plan view thereof; taken along lines 11-11 of FIG. 6;

FIG. 12 is an enlarged partial front elevational view thereof; taken along lines 12-12 of FIG. 1;

FIG. 13 is an enlarged right side elevational view thereof;

FIG. 14 is an enlarged vertical cross-sectional view thereof; taken along lines 14-14 of FIG. 9;

FIG. 15 is an enlarged vertical cross-sectional view thereof; taken along lines 15-15 of FIG. 9;

FIG. 16 is an enlarged vertical cross-sectional view thereof; taken along lines 16-16 of FIG. 9;

FIG. 17 is an enlarged partial front, top and right side perspective view thereof taken along lines 17-17 of FIG. 1;

FIG. 18 is an enlarged partial front, top and right side perspective view thereof taken along lines 18-18 of FIG. 1;

FIG. 19 is an enlarged partial front, top and right side perspective view thereof taken along lines 19-19 of FIG. 1;

FIG. 20 is a front elevational view of a fin-plate for heat exchanger, showing an alternate embodiment of our new design;

FIG. 21 is a rear elevational view thereof;

FIG. 22 is a left side elevational view thereof;

FIG. 23 is a right side elevational view thereof;
FIG. 24 is a top plan view thereof;
FIG. 25 is a bottom plan view thereof;
FIG. 26 is an enlarged left side elevational view thereof;
FIG. 27 is an enlarged partial front elevational view thereof;
taken along lines 27-27 of FIG. 20;
FIG. 28 is an enlarged partial front elevational view thereof;
taken along lines 28-28 of FIG. 24;
FIG. 29 is an enlarged partial top plan view thereof; taken
along lines 29-29 of FIG. 24;
FIG. 30 is an enlarged partial bottom plan view thereof; taken
along lines 30-30 of FIG. 25;
FIG. 31 is an enlarged partial front elevational view thereof;
taken along lines 31-31 of FIG. 20;
FIG. 32 is an enlarged right side elevational view thereof;

FIG. 33 is an enlarged vertical cross-sectional view thereof;
taken along lines 33-33 of FIG. 28;
FIG. 34 is an enlarged vertical cross-sectional view thereof;
taken along lines 34-34 of FIG. 28;
FIG. 35 is an enlarged vertical cross-sectional view thereof;
taken along lines 35-35 of FIG. 28;
FIG. 36 is an enlarged partial front, top and right side per-
spective view thereof; taken along lines 36-36 of FIG. 20;
FIG. 37 is an enlarged partial front, top and right side per-
spective view thereof; taken along lines 37-37 of FIG. 20;
and,
FIG. 38 is an enlarged partial front, top and right side per-
spective view thereof; taken along lines 38-38 of FIG. 20.
